UNITED STATES PATENT OFFICE

EUGENE W. CARUTHERS, OF SECANE, PENNSYLVANIA

RAIL JOINT

Application filed May 9, 1928. Serial No. 276,347.

My invention relates to splice bars for use in tying together the adjoining ends of the rails of railroad tracks.

One purpose of my invention is to give the head of a splice bar a contour that will insure a live joint between the bar head and rail head even after the bar has from long service worn inwardly to a seat against the web of the rail.

10 A further purpose is to avoid permanent engagement between the bar head and rail fillet even after the bar has from long service worn inwardly to a seat against the web of the rail.

15 A further purpose is to change the vertical alinement of a splice bar after its head portion has worn to a seat against the web of the rail, drawing the foot portions of the cooperating bars inwardly about an abutment 20 below the rail fillet as an axis and thereby free the engagement between the rail fillet and the bar head and maintain a live joint between the bar and rail where formerly the joint has become permanently dead as soon 25 as the bar head reaches a seat on the web of the rail.

30 A further purpose is to relieve the lower portion of the base of the bar so as to adapt it to move inwardly after the top of the bar has found a seat against the web of the rail.

35 A further purpose is to accommodate the sectional area of the track bolts which unite cooperating splice bars to the length of the bolts, thereby maintaining any desired definite strain for a given bolt tension irrespective of bolt length.

40 A further purpose is to provide interfitting arcuate bearing surfaces between the head and nut or washer portions respectively of a bolt member and the cooperating splice bars tied together by the bolt to form a rail joint. I may make the interfitting arcuate bearing surfaces either spherical or cylindrical and may locate these bearing surfaces between the head of the bolt and the outside of one splice bar at one end of the bolt and between the cooperating splice bar and a nut or a washer beneath a nut at the other end of the bolt.

45 A further purpose is to vary the contour

of the splice bars according to service conditions and also according to the material of the splice bars and of the rail.

50 A further purpose is to lessen the requisite sectional area of track bolts by lessening the 55 distance between the web portions of the cooperating splice bars. I thus lessen the cost of track bolts by providing a contour of splice bar that permits the use of smaller and shorter bolts than have hitherto been considered necessary. 60

55 A further purpose is to provide the nuts of track bolts with extension portions for wrench holding thereby permitting the use 65 of greater outward extension of the head portion or foot portion, either or both, of the splice bar without interfering with the adaptation to easy tightening of the nuts.

70 A further purpose is to provide a splice bar with a contour that will adapt it to pivot 75 slidly upon the web portion of the rail at the inside lower edge of the bar head after the bar head has worn to a seat against the web, resulting in a slight canting and upward movement of the bar so as to support the lower 75 portion of the rail head at a point out from the rail fillet.

80 A further purpose is to maintain supporting engagement between the under side of a rail and the head of a splice bar at points outwardly from the rail fillet while the bar head is finding a seat against the rail web.

85 Further purposes will appear in the specification and in the claims.

While I show my invention in forms that differ in detail, as with respect to the bolt connection between the cooperating splice bars, size and contour of bar foot and location of bar web with respect to its distance 90 from the rail web, I have elected to illustrate the invention with but a single contour of rail and but a single contour of inwardly presented surface on the bar head.

95 Figure 1 is a vertical section through a rail joint embodying my invention, showing the splice bars in three positions.

Figure 2 is a reduced scale broken top plan view of structure shown in Figure 1.

100 Figures 3 and 4 are cross-sections corre-

sponding generally with Figure 1 but showing slightly modified forms.

Figures 5, 6, 7, 8 and 9 are fragmentary views illustrating different forms of arcuate connections between the splice bar and the nut and bolt members at the nut end of the bolt, each of the forms shown having certain advantages that may under certain conditions make it desirable as compared to any of the others illustrated.

Figure 1 shows a form of splice bar very similar in general appearance to one that has hitherto been widely used, but from which it differs at the head to prevent the head from wearing to a dead seat against the rail head fillet, and differs at the foot to permit the foot to wear inwardly after the head has worn to a seat against the rail web.

The figure shows the bars in three positions, a full line contour showing the rails in their initial positions, a dot-and-dash line contour showing the position of the bars when they have worn horizontally inwardly to seat against the rail web, (after perhaps two to three years of service,) and a dotted line contour showing their canted position at a considerably later period, with a freed rail fillet and a live bearing under the rail head.

Like numerals refer to like parts in all figures.

Describing in illustration and not in limitation and referring to the drawings:—

In the past splice bars have been given a form such that the splice bar heads after a period of considerable service find permanent seats against the rail head fillets. This has produced undesirable "dead" joints from the time that the bar heads wear into engagement with the rail fillets, "dead" joints being joints that do not adequately support the under side of the rail head at points out beyond the rail fillets. The wedging action of the support has been lost.

One of the principal objects of my invention is to prevent the rail heads from wearing into "dead" seats against the rail fillets and by this means to maintain a supporting engagement under the rail head at points further out than the rail fillet and thereby to increase materially the effective life of the joint.

In Figures 1 and 2 adjacent ends of rails 10 and 11, supported upon suitable tie-plates 12 and 13 and ties 14 and 15, are held together intermediate the ties by preferably interchangeable splice bars 16 and track bolts 17.

The rails 10 and 11 are shown of a well-known type and the splice bars 16 are shown with a sectional contour that is very similar in general appearance to that of a type of splice bars that has been widely used in the past.

The illustrated contour differs only slightly from that of the prior art, but differs in a

way that results in a material increase in the effective life of the bar.

I have extended the lower part of the bar head 18 somewhat inwardly to provide a fulcrum 19, in position to ultimately engage the rail web 20 of the rail.

I have also decreased the outer curvature of the head portion 21 that is presented toward the rail fillet 22 making its radius of curvature as great as or greater than the radius of curvature of the fillet 22, and have also made the lower contour of foot 23 of the bar such as to adapt the foot to gradually ride inwardly up the flange portion 24 of the rail after further inward movement of the bar head has been stopped by the bar head engaging the rail web.

The forward relief of the foot at 25 should be sufficient to permit the more nearly central portion 27 to ride up the rail flange and in the same way the outer relief at 26 should be sufficient to avoid locking the bar from vertical canting.

In Figure 1 the initial position of the splice bars is shown in full line contour. The sloping upper surface 28 of the bar head engages the correspondingly sloping outer portion of the lower surface of the rail head and the central portion 27 of the foot engages the top of the rail flange at a relatively considerable distance from the rail web.

After the joint has been in service for a considerable period during which period the bolts have been periodically tightened the spliced bars will occupy some such position as that indicated by the dot and dash line 29, the bearing surfaces between the rail head and bar head and between the rail flange and bar foot having progressively worn away until the bar head finds a seat against the web of the rail as indicated in the dot and dash line.

In the illustration the adjoining contours of the rail head and bar head are coincident, the curved portion 21 of the bar head temporarily fitting the fillet 22 of the rail.

Optionally the radius of curvature of the bar head contour at 21 may be made greater than that of the rail fillet in which event the two surfaces will never quite coincide but I prefer to make the curvature of the bar head at 21 as small as but no smaller than that of the rail fillet.

I make this radius of curvature at least as small as that of the rail fillet in order that the rail fillet may never determine the inward position of the head, a condition that has existed with the bars of the prior art after the bars have worn to seat against the rail fillets, and a condition which I have found gives a "dead" connection between the rail head and the bar head.

I preferably make the radius of curvature not much smaller than that of the fillet because this would mean an unnecessary elimi-

nation of metal from points on the head relatively far from the neutral axis of the bar.

The dot and dash position corresponding to line 29 may be considered as a temporary one that the bar occupies for a short period before it begins to be canted by inward travel of the foot after the corresponding inward travel of the head has been stopped by an engagement between the bar head and rail web.

10 Further wear and additional tightening of the bolts results in drawing the lower portion of the bar inwardly with respect to the upper portion until the bar occupies some such position as that indicated by the dotted line 30.

15 The result of thus moving the bar foot further in than the bar head is to relieve the engagement between the curved portion 21 of the bar head and the rail filler. This may be seen by examination of the dotted line 30 which shows the curved portion of the head 20 at some little distance from the fillet.

The exact position of the upper surface of the bar head and of the lower surface of the rail will vary with variant service conditions 25 and for this reason the illustration should be taken as merely a diagrammatic one to bring out the fact of the freeing of the rail fillet and the maintenance of engagements between the rail and bar head upon each side of the 30 fillet but not at the fillet.

It will be seen that the dead connection between the bar head and rail fillet is avoided, the rail head being effectively supported at points further out than the fillet and the effective life of the joint is materially increased.

If the bearing surfaces between the bars and bolt members are flat, one flat surface 31 (Figure 1) of one bar supporting a flat surface 32 under the bolt head 33 while the corresponding flat surface on the other bar supports a flat surface 34 under a bolt washer 35, then any relative canting of the bars, produced by tightening the bolts with inward movements of the foot portions of the bars 40 without a corresponding inward movement of the bar heads, will stretch the upper fibers of the bolts more than the lower fibers and thereby produce greater stresses in the upper bolt 45 fibers.

50 I preferably provide interfitting arcuate bearing surfaces between the bolt head and one splice bar and the bolt nut or bolt washer and the other splice bar to avoid these uneven stresses and strains when the bars are canted vertically to maintain live joint connection between the rail heads and bar heads.

I have not illustrated these interfitting arcuate connections in Figure 1, which is intended primarily to illustrate the canting of the bars and the maintenance of the live head support. A bar of the prior art is there modified to embody some of the features of my invention, but without effecting much change in 65 the sectional contour and placement of metal.

This general type of bar has been built upon the theory that the upper and lower section moduli of the bar should be substantially equal. My invention applies whether this be true or not and has, therefore, been applied to 70 both forms.

It will be understood that the strength of the upper portion of the bar may be considered as determined by the upper section modulus, which is the moment of inertia of the 75 whole bar, divided by the distance from the horizontal axis passing through the center of gravity to the extreme upper fiber, and that the strength of the lower portion of the bar is determined by the lower section modulus, 80 which is the ratio between the same moment of inertia of the whole bar, divided by the distance from the same horizontal axis passing through the center of gravity of the bar to the lower extreme axis.

I have discovered that this theory that the upper and lower section moduli of the section should be substantially equal is basically incorrect and that as a matter of fact in any usual conditions of service the head portions 90 of the bars should be considerably stronger than the foot portions if the two are to wear out simultaneously and have disclosed and claimed bars having a greater upper section modulus than lower section modulus in an application, Serial No. 276,348, copending here- 95 with.

Figure 3 shows a bar substantially like that of Figure 1 except that the outwardly extending flange portion 36 of the foot has been removed to a point even with the outside edge 100 of the rail flange and also in that the bearing surfaces between the bars and bolt members are interfitting arcuate surfaces instead of flat as in Figure 1.

The effect of cutting off a major portion of the flange 36 is to raise the center of gravity of the bar and to make its lower section modulus less than its upper section modulus, both of which I have found desirable. However 110 cutting off the outer portion of the flange correspondingly weakens the foot flange in so far as it is used to prevent any distortion of the bar when the bolts are tightened.

The arcuate interfitting surfaces between 115 the bolt member and the respective bars may be either spherical or cylindrical, either form having certain advantages and in certain cases being most desirable, and both forms permitting the bars to cant without an introduction of uneven stresses and strains either in the bolt or in the bar members.

An arcuate cylindrical concavity 37 along the outside of the splice bar web gives a section that is easily rolled and that has a minimum thickness along the middle of the web, which is in accord with an efficient placement 125 of the metal of the flange.

The convexly curved spherical bolt head 130 surface 37' fitting one cylindrical surface and

the convexly curved spherical washer surface 37² fitting the other cylindrical surfaces are also surfaces very easily formed when manufacturing the bolts and washers respectively.

5 The interfitting cylindrical bearing surfaces are of course not adapted to relative rotation so that washers are needed under the nuts when this type of web and bolt bearing connection is used.

10 There are some advantages in making the interfitting arcuate bearing surfaces between the bolt members and bars spherical instead of cylindrical and when this is done the washer under the nut may be omitted, the inner 15 end 39 (Figure 6) of the nut being formed with a spherical bearing surface to seat in a spherical depression on the web of the bar. The bolt must then be of non-circular section to prevent turning in a non-circular bar open- 20 ing.

The omission of the washer shortens the distance between the nut and head of the bolt, thereby proportionately lessening the total longitudinal strain or stretch of the bolt 25 which is sometimes deemed quite desirable.

If the bolt is made of a perfectly elastic stock, that is of a bolt stock that does not take a permanent strain, the strain disappearing when the stress is removed, and the strain 30 and stress remaining continuously proportional, it may be not at all disadvantageous to have the bolt long with the resultant relatively great total elongation when the nuts are tightened, in that the very perfect 35 elasticity of the bolts then maintains a very uniform pressure against the splice bars, resulting in a very live joint.

On the other hand when the bolts are made 40 of a more usual stock that is only imperfectly elastic, they take a permanent set when tightened and it is then desirable to limit the bolt elongation to a definite value, in that this 45 limits the undesirable permanent set of the bolt. It will be evident that the total permanent set of a bolt incident to a given total pull will vary directly with the effective length 50 of the bolt and that a shorter bolt should also be sectionally smaller if the permanent set of the bolt is to be the same as that of the longer bolt.

I may accommodate the sectional area of 55 the track bolts to their effective length, using shorter and optionally smaller bolts when conditions are such that it is desirable to limit the total elongation of the bolts when 60 the nuts are tightened to a definite value, or using longer bolts when conditions make it desirable to have a fairly high elongation, 65 which is usually only the case when the material of the bolt is such as to very perfectly maintain strict proportionality between longitudinal stress and longitudinal stretch without any substantial permanent set when 70 the stress has been removed.

It may sometimes be desirable to reduce the stress in the bolts to a definite value below which it has been found stress and strain are substantially perfectly proportional and in this event the sectional area of the bolt is determined by the total longitudinal pull from 75 tightening the nuts while the length may be desirably increased to increase the liveness of the joint by increasing the bolt's elongation.

When conditions make it desirable to use 75 long bolts I may use washers under the nuts, as in Figures 3, 4, 5 and 8 and use a form of splice bar having web portions spaced far from the web of the rail as in Figure 3, while if conditions are such as make it desirable to 80 use short bolts, I avoid the use of washers (Figures 6 and 7), and form the splice bars with webs relatively close to the rail web.

It will be seen that the spherical bearing 85 surfaces between the bar and nut members are preferable when shorter bolts are desirable.

It is obvious that the advantage of making 90 the bearing surfaces between the bars and bolt members of an interfitting arcuate contour is one that avoids uneven stresses and strains in the bolts and in the webs of the bars when the bars are relatively canted and also one that avoids uneven stresses in the bolt if 95 the bolt becomes bent, which is not at all unusual.

Bolts become bent during service most frequently in a direction longitudinal of the rail, the bending being due to stresses tending to 100 pull the rails apart longitudinally.

When a bolt becomes bent longitudinally of the rail the spherical seating of the nut and head members is preferable to the cylindrical, in that the spherical seating more effectively avoids uneven stresses and strains when the 105 bolts are tightened.

In the form shown in Figure 3 the strength 110 of the head of the bar is materially greater than that of the foot. There are very heavy shear stresses upon the portions of the bars that are at the ends of the rails.

If these shear stresses are perfectly supported, the functioning of the splice bars as beams subjected to bending moments first up and then down is to a considerable extent avoided. For this reason, and also for the reason that the stresses on the bar are to a very considerable extent the result of blows or sudden impacts, the section modulus of the upper portion of the bar needs to be under usual conditions of service considerably greater than that of the lower.

The head has to be strong enough to stand up under impact stresses and blows that have a relatively smaller effect at the foot portion 125 of the bar.

Both the head and foot must have a very considerable strength against horizontal distortion when the bolts are tightened, that is, should have reasonably high section moduli 130

with respect to a vertical plane through the center of gravity of the bar.

This strength in horizontal direction should be sufficient to prevent any distortion of the bars along their lengths incident to tightening the bolts, and for this reason the foot should usually be fairly heavy but less heavy than the head.

The actual dimensions of both the foot and head will preferably vary according to service conditions, both being big enough to satisfactorily meet the intended service without bending inwardly at the bolts when the bolts are tightened but the foot portion should not be heavier than is needed to do this. It is probable that the foot section shown in Figure 3 is smaller than in many cases will be desirable.

In Figure 4 I have moved the web portion of the bars inwardly as compared to the bars shown in Figure 3, and have also increased the size of the foot 23'.

The line 40 between the bearing surfaces at the foot and head respectively here passes through the web portion of the bar.

The positions of the bar webs close to the rails made possible by the large lateral overhangs of the head and foot flange portions at 41 and 42 permit the ready use of bolts of shorter length in order to accommodate the length of the bolt to service conditions.

In Figure 4 I show upon the bolt a washer member 43 of sufficient length to permit the use of a square nut 44 outside of the outwardly extending flange portions of the bar.

It is usually quite advantageous to use square nuts instead of hex nuts because of the better grip they afford a wrench.

It will be seen that the effective length of the bolt is then sufficient to reach from the outside of the web of one bar to a point beyond the laterally extending flanges of the other bar.

Obviously the nut member may extend inwardly to any desired degree toward the web of the bar, and in Figure 5 I illustrate this, a nut 45 being provided with a reduced portion 46 between the flange portions of the bar and a washer 47 of any desired length that is seated against the web of the bar. In this illustration the nut member is not threaded throughout its length, one end, shown in the figure as the inner end, being given a sectional interior greater than the threaded portion of the bolt. This gives a bolt that is effectively long and will be desirable when the bolt stock has very low permanent set under service conditions.

In Figure 6 I show the nut and washer member integral. The seat in this case should be spherical and only the inner end portion of the nut need be threaded. The advantage of the nut, shown in Figure 6, lies in shortening the effective length of the bolt, which in many cases, may mean a bolt not only of

lesser length but also of lesser diameter in that it is not infrequently deemed desirable to maintain the total stretch of the bolt when the nuts are tightened at a definite value.

It will, of course, be obvious however that reduction in the bolt area and reduction in bolt length will mean a greater stress upon the material of the bolt if the total stretch when the nuts are tightened is to be the same as before.

The form shown in Figure 7 illustrates a nut 48 of sufficient length to afford ample wrench hold and still avoid the use of a washer. The nut may be threaded at any desired portion of its length to obtain any desired effective length of bolt and is illustrated as threaded at the outer end of the nut. The nut is provided with an enlarged bore wherever it is not threaded, as toward its inner end. In this figure as in the other figures the nuts may be square or hex as desired.

When the nut is threaded only at its outer end the effective length of the bolt is relatively great. With some service conditions and bolt characteristics this may be very desirable, for example, when the bolt stock has high elasticity and the tension stress does not exceed a predetermined safe value. A live joint is then obtained by giving the bolt a sectional area to limit its tension stress during service to the predetermined value. The bolts are made long to increase the uniformity of the clamping force of the bolts upon the splice bars.

Figures 8 and 9 may illustrate a slight modification of the form shown in Figure 6 in that the arcuate seat 49 may be cylindrical instead of spherical and a washer 50 may be inserted between the nut and the web at the bar.

In Figure 8 the inner end 51 of the bore of the nut is threaded while the nut is extended at 52 beyond the head and foot lateral flanges a distance sufficient to afford a wrench hold. In Figure 9 the outer end of the bore of the nut is threaded and the interiorly enlarged inner end is in effect merely an inner extension of the outer nut portion for engagement with the washer.

It will be seen that I have provided a construction that materially increases the effective life of the splice bars by avoiding a "dead" engagement between the splice bars and the rail fillets after the bar heads have worn inwardly so as to engage the opposite sides of the rail web.

I have also provided a novel construction that avoids uneven stresses and strains in the bolts and splice bars during this period of increased life and have also pointed out in what way the relations between the bolt lengths and bolt areas need to be varied to accommodate differences in the elastic properties of the bolts and splice bars, so as to

permit an intelligent selection of bolt dimensions according to variant service conditions and variant characteristics of the stock materials, and have disclosed the method of varying dimensional and form characteristics of the bar foot as well as the characteristics of the bolt members to generally improve the character and life of the joint.

In view of my invention and disclosure 10 variations and modifications to meet individual judgment or particular need will doubtless become evident to others skilled in the art, to obtain all or part of the benefits of my invention without copying the structure shown, and I, therefore, claim all such 15 in so far as they fall within the reasonable spirit and scope of my invention.

Having thus described my invention, what 20 I claim as new and desire to secure by Letters Patent is:

1. The method of maintaining a supporting engagement between the under side of a rail head and the head of a splice bar, after the splice bar has engaged the rail web and 25 points outwardly beyond the rail fillet, which consists in providing the inner portion of the bar head with a fulcrum adapted to engage the web of the rail below the fillet after continued service and in drawing the lower portion 30 of the bar inwardly with respect to the bar head so that it bears upon the web to free the fillet, and rides upwardly to engage the rail head beyond the fillet.

2. A splice bar for joining the adjacent 35 ends of railroad track rails having a head initially fitting against the outer portion of the under side of the rail head and fitting against the top of the rail flange at its foot, a fulcrum on the head of the bar adapted to 40 engage the rail web after continued wear between the engaging surfaces of the rail and bar, the bar having a curved contour between the fulcrum and the bearing surface of the head of radius not less than the radius of the 45 rail fillet, and said bar having also a foot supported upon the rail flange that is relieved upwardly upon each side of its bearing surface at the rail flange.

3. In a rail joint, a splice bar, a head there- 50 of having a fulcrum adapted to engage the rail web after wear has taken place, and a foot on the lower portion of the bar resting upon the rail flange and curved upwardly at front and rear for adaptation to inward 55 movement about the fulcrum, after the fulcrum engages the rail web.

4. In a rail joint, a splice bar having a head 56 and a foot, a fulcrum on the head adapted to engage the rail web after wear has taken 60 place to limit the inward movement of the bar head without limiting the inward movement of the foot, the said foot being relieved upwardly at each side of its bearing upon the rail flange, and a bolt member holding the bar 65 to place.

5. In a rail joint, a splice bar having a head and a foot, a fulcrum on the head adapted to engage the rail web after wear has taken place to limit the inward movement of the bar head without limiting the inward movement of the foot, the said foot being relieved upwardly at each side of its bearing upon the rail flange, and a bolt member holding the bar to place and having an arcuate socket connection therewith.

6. In a rail joint, a splice bar having a head and a foot, a fulcrum on the head adapted to engage the rail web after wear has taken place to limit the inward movement of the bar head without limiting the inward movement of the foot, the said foot being relieved upwardly at each side of its bearing upon the rail flange, and a bolt member holding the bar to place and having a ball and socket connection therewith.

7. In a rail joint, a rail, a pair of splice bars each having the web of the splice bar nearer the inner flange extremities than the outer flange extremities of the bar permitting the use of a short bolt, a bolt therethrough and a nut for the bolt extending beyond the outer bar flange extremities for access to the nut.

8. In a rail joint, a rail, a pair of splice bars on opposite sides thereof having the heads of the bars nearer to the rail web than the feet thereof and adapted to swing about the heads as axes and a bolt passing through the splice bars and having bearing against the splice bars accommodating the tilting of the splice bars.

9. In a rail joint, a rail and apertured splice bars on opposite sides of the rail, the splice bars being grooved horizontally to accommodate the bolts for the splice bars and bolt-heads and nuts or washers being curved in vertical contact planes with the splice bars to accommodate tilting of the splice bars.

EUGENE W. CARUTHERS.
